HANGER RACK FOR INTRAVENOUS BOTTLES

John W. Pryor, 5753 Desert View,
La Jolla, Calif. 92037

Filed Mar. 19, 1971, Ser. No. 126,381

Term of patent 14 years

Int. Cl. D24—02; D8—03
U.S. Cl. D83—1 B

Fig. 1

Fig. 2

Fig. 3

FIG. 1 is a side elevational view of a hanger rack for intravenous bottles, showing my new design;

FIG. 2 is a view as taken from the left hand side of FIG. 1; and

FIG. 3 is a top plan view thereof.

I claim:

The ornamental design for a hanger rack for intravenous bottles, substantially as shown.
